PORTABLE GREASE GUN

Hobart N. Durham, Munsey Park, and Philip M. Carter, Yonkers, N. Y.

Application January 9, 1942, Serial No. 426,170

10 Claims. (CI. 222—56)

This invention relates to improvements in devices for dispensing materials of a liquid or semi-liquid nature under pressure, more particularly, devices of the nature aforesaid particularly adapted for lubricating vehicles, machinery, etc. provided with fittings at the bearings to be lubricated.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrates one embodiment of the invention, and together with the description, serves to explain the principles of the invention.

Objects of the present invention are: to provide an improved dispensing device particularly applicable to and useful for the lubrication of vehicles, machinery, etc. and offering certain advantages in diversification of utility; to provide a dispensing device embodying a power driven dispensing pump which will be automatically disconnected from its prime-mover and immobilized when the back pressure on the pump exceeds a predetermined value and will be automatically reconnected to its prime-mover and mobilized when the back pressure on the pump is less than a predetermined value; to provide a dispensing device embodying a prime-mover which will be controlled by the pumping demand; to provide a dispensing device embodying a prime-mover and a pair of pumping units severally or jointly operable by the prime-mover; and, to provide a dispensing device embodying automatic safeguards against overloads on the pumping system.

To this end, as at present preferably embodied, and as applied to a portable lubricant dispensing device, a power driven pump for delivering lubricant under pressure through a valve controlled delivery nozzle, is mounted on a small mobile vehicle which may be easily manually wheeled from one place of usage to another. The induction side of the pump communicates with a storage vessel carried by the vehicle. Lubricant is supplied from this vessel to the pump chamber from which latter the lubricant is delivered under pressure to the delivery nozzle which communicates with the induction side of

the pump. A prime-mover mounted on the vehicle drives the pump through suitable drive mechanism embodying an automatic coupling device. This coupling device functions automatically to couple and uncouple the prime-mover and the pump in response to speed changes in the prime-mover occasioned by pressure changes in the pumping system. A speed change of the prime-mover is automatically effected by means of speed control mechanism responsive to selected pressure changes in the pump chamber to which it is connected. The speed control mechanism is so designed that a predetermined increase in the pressure within the pump chamber over the normal pumping pressure, as would be occasioned, for example, by closing the valve in the delivery nozzle, will actuate the speed control mechanism so as to decelerate the prime-mover to a lower speed value. This speed change causes the coupling device automatically to discontinue the transfer of power from the prime-mover to the pump which is thereby immobilized so as to prevent a further and possibly harmful pressure increase. When the pressure acting upon the speed control mechanism is lowered, as would result, for example, from opening the delivery nozzle valve, the speed control mechanism is restored to its original operating condition and thereby accelerates the prime-mover to its original speed value. This latter speed change causes the coupling device automatically to resume the transfer of power from the prime-mover to the pump which is again mobilized. The extent of the speed change of the prime-mover is dependent upon the sensitivity of the speed control mechanism, but the prime-mover continues to operate, at a reduced or idling speed, even though the pump is immobilized. The power available may be used therefore for operating an air compressing unit which is mounted upon the vehicle and is connectable at will to the prime-mover so as to be driven thereby regardless of whether the dispensing pump is mobilized or immobilized.

In the preferred embodiment of the invention the prime mover comprises a relatively small gasoline engine, and this is connected to the pump by means of an optionally effective connection whereby the engine may be warmed up without being under load, and also permitting air to be compressed by the engine running at full speed without operation of the pump. These connecting means also preferably permit the pump to be connected to the engine without stopping the engine.

Of the drawing:

Figure 1 is a side elevation, partly in section, of one embodiment of the present invention; and

Figure 2 is a fragmentary detail, partly in section of connecting means between the engine and pumps.

It will be understood that the foregoing general description, and the following detailed description as well, are exemplary and explanatory, but are not restrictive of the invention.

Referring now in detail to the embodiment of the invention illustrated by way of example in the accompanying drawing, a prime-mover 1 is shown supported on a platform 2 in spaced relation to a small portable truck 3 having the front and rear wheel structures 4 and 5 respectively.

The platform 2 to which the prime-mover 1 is secured by bolts 6, rests upon structural members 7 which are secured to the platform by bolts 8 and to the truck 3 by bolts 9.

The prime-mover 1, as embodied, is preferably a self-contained power unit although the use of power units to which energy is supplied from a remote source is within the contemplation of this invention. As here embodied, the prime-mover 1 is shown as a single cylinder gasoline engine having the starting crank 10, carburetor 11 and fuel tank 12. Speed control of the engine is attained by means of a throttle valve 13 connected by link mechanism 14 to speed control mechanism 15.

The engine crankshaft terminates in a pulley 16 affixed thereto and adapted to be engaged by and to drive the pulley 17 of an air compressor 18 which discharges into the storage tank 19 for holding air under suitable pressure.

The air compressor 18 is mounted in trunnion bearings 20 upon a platform structure 21 carried by the truck 3. A cammed lever 22 journaled in the platform structure 21 is provided for tilting the compressor on the bearings 20 so as to place the pulley 17 in power transmitting relation with the pulley 16, at will. Various other expedients for effecting power transfer at will from the prime-mover 1 to the compressor 18 will be apparent to those skilled in the art.

The output of the engine 1 is deliverable through a drive mechanism embodying an automatic coupling device, to a pump by which the material to be dispensed is deliverable under pressure through a valve controlled delivery nozzle. As here embodied, an automatic clutch 25 on the engine pulley is connected by a V-belt 28 to a pulley 29 which is affixed to a worm gear 30.

The automatic clutch or coupling device 25, as embodied, effects a power transfer from the engine 1 to the worm gear 30 of the pumping mechanism, to be described hereinafter, upon a speed-up of the engine 1. It effects a termination of this power transfer upon a slowing down of this engine. As here embodied, the clutch 25 comprises a driving element 26 fixed to the engine crankshaft, and a driven element 27 journaled on the engine crankshaft. The clutch is preferably of a speed-controlled centrifugal, for example, such as the clutch type disclosed in U. S. Patent No. 2,258,157 granted October 7, 1941, to E. F. Kohl. In accordance with the teachings of that patent, the driving and driven elements 26 and 27 respectively, are adapted to be automatically locked to or released from each other as the case may be by means of locking members (not shown), when the engine speed

attains or recedes from a selected value, consequent upon a change in the setting of the throttle valve 13.

The worm gear 30 is journaled at either end on broad and ample bearings in a gear housing 31 carried by the truck 3.

The gear housing 31 encloses a cam gear 32 and a cam follower 33. The cam gear 32 is journaled in the housing 31 by means of a shaft 10 34 so as to be driven by the worm gear 30 and has one face provided with an eccentric 35 which engages the follower 33.

The follower 33 is mounted in the housing 31 for reciprocable movement in bearings 36 and 15 37 and is detachably secured at one end to the piston rod 38 of a piston and cylinder type of dispensing pump 39, preferably of the type shown in Fig. 3 of U. S. Patent No. 1,956,144 granted April 24, 1934, to W. Y. Brown.

The dispensing pump 39, as here embodied, has its induction side in communication with a storage vessel 40 mounted on one end of the truck 3. The eduction side is connected by a delivery pipe 41 to a valve-controlled delivery nozzle 42. The nozzle 42, as here embodied, is a high pressure so-called "grease-gun" having a manually operable valve control lever 43. The eduction side of the pump is also connected by a pipe 44 to the pressure operated speed control mechanism 15, so that whatever pressure is built up in the pumping system is imparted to the speed control mechanism.

The speed control mechanism 15, as embodied, functions to move the throttle valve 13 toward a closed position thereby to decelerate the engine 1 to a lower speed value, when the pressure built up by the pump 39 exceeds a selected value. Such a condition would result from releasing the valve control lever 43 when the pump is operating. In consequence of this deceleration, the clutch 25 automatically uncouples the engine from the pump drive mechanism and the pump 39 ceases to function. The attained pressure is maintained by the usual check-valve mechanism 45 of the pump 39 until the valve control lever 43 is depressed so as to permit lubricant to flow under the attained pressure from the delivery nozzle 42. The resultant pressure drop is communicated through the pipe 44 to the speed control mechanism 15 which together with the throttle valve 13 is in consequence automatically restored to its initial condition. The resultant acceleration of the engine 1 to the original speed value energizes the clutch 25 so as again to mobilize the pumping mechanism and thereby complete the cycle.

The speed control mechanism 15, as here embodied, comprises a piston 45 reciprocably mounted in a cylinder 46 and in a casing 47. The casing 47 is fastened to the flywheel casing of the engine 1 and carries the cylinder 46. The cylinder 46 is connected by the pipe 44 with the eduction side of the pump 39 so that the attained fluid pressure is imparted to the piston 45. A coil spring 45a is positioned around the piston 45 between the casing 47 and yoke arm 48. The arm 48 extends from the piston 45 to the opposite sides of a shaft 49 which is slidably and rotatably mounted in the casing 47 for reciproca-

ble movement parallel to the piston 45. The shaft 49 is internally threaded at one end and engages one end of a member 50 which in turn is pin-connected to the link mechanism 14. Thus, manual rotation of the shaft 49 will effect a change in the setting of throttle valve

13. The shaft 49 is provided with a shoulder 51 which normally abuts the casing 47 thereby to fix the "throttle open" position. A second shoulder 52 is adapted to be engaged by the arm 48 after the latter has been moved a short distance as the piston travels. A certain amount of pressure thus may be built up before the lost-motion is taken up and shaft 49 moves throttle valve 13 against the resistance offered by the return-spring 53. The spring 53 is secured at one end to the link mechanism 14 and at the other end to the engine 1 and tends to hold throttle valve 13 open. Thus it will be apparent that as the fluid pressure applied to the piston 45 increases, consequent, for example, upon release of control lever 43 while the pump 39 is running, the piston 45 moves to the left against the resistance of the spring 45a. The arm 48 engages the shoulder 52 and upon further pressure increase moves the shaft 49 to the left. This movement is conveyed through the link mechanism 14 to the throttle valve 13 which is moved against the resistance of spring 53 toward an idling position. The reduction in speed causes the speed responsive clutch 25 to uncouple the engine 1 from the pump drive mechanism and thereby immobilize the pump 39. While thus idling, or while at its high speed, the engine 1 may, if desired, be coupled manually by means of the cam lever 22 to the pulley 17 of the air compressor 8, if it is desired to operate this auxiliary unit. When the valve control lever 43 is again depressed, the fluid pressure on the piston 45 is lowered. Piston 45 and shaft 49 move to the right under the action of springs 45a and 53 respectively. This movement reopens the throttle valve 14 and accelerates the engine speed from an idling speed of say, 400-500 R. P. M., to a high torque speed of say, 2000-2500 R. P. M., at which clutch 25 automatically couples the engine 1 and the pump drive mechanism and thereby mobilizes the pump 39.

In order to provide for warming up the gasoline engine 1, so that it may develop its full power in relatively short time, means are provided for optionally disconnecting the piston 38 from the follower shaft 33'. As embodied, these means comprise the pivoted latch fingers 60 which are mounted in the member 61 pinned to the end of rod 38 and are normally held in engagement with the groove 62 in the end of shaft 33' by compression of the spring 63 whereby the pump is driven by the engine. A manually movable collar 65 is provided having an internally bevelled mouth to fit over the divergent ends 66 of fingers 60 to hold the fingers 60 out of groove 62, thereby disconnecting the pump from the engine and allowing the engine to run at any speed, idly or in driving relation with the air compressor. When the engine has warmed, collar 65 may be moved to latching position by knob 67 operating in a slot in the frame member 68, and on the next approach of the shaft end 33' to the plunger 38, the fingers 60 will engage in groove 62 to cause pumping of grease to be resumed, again placing the engine under control of the pressure responsive unit 15.

Certain features and sub-combinations of this invention are of utility and may be employed without reference to other features and sub-combinations thereof and various changes may be made in details within the scope of the appended claims without departing from the spirit of this invention. This is contemplated by and within

the scope of the appended claims and this invention is not to be limited to the specific details shown and described.

Having thus described the invention, what is claimed is:

1. A liquid dispensing device including in combination a prime-mover; a liquid pump; means for automatically coupling and uncoupling said prime-mover and said pump in response to a speed change of said prime-mover; and, means for effecting a change in the speed of said prime-mover in response to a change in the pumping pressure.

2. A liquid dispensing device including in combination a prime-mover; a liquid pump; means for automatically coupling and uncoupling said prime-mover and said pump in response to a speed change of said prime-mover; and, pressure responsive means for effecting a change in the speed of said prime-mover in response to a change in the pumping pressure.

3. A liquid dispensing device including in combination a prime-mover; a liquid pump; a valve-controlled delivery nozzle communicating with the eduction side of said pump; pressure-responsive means for controlling the speed of said prime-mover communicating with the eduction side of said pump; and, centrifugal clutch means for automatically coupling and uncoupling said prime-mover and said pump in response to a speed change of said prime-mover.

4. A liquid dispensing device including in combination a prime-mover; a liquid pump; pressure-responsive means for controlling the speed of said prime-mover, said means having a pressure chamber communicating with the eduction side of said pump; and, centrifugal clutch means for automatically coupling and uncoupling said prime-mover and said pump in response to a change in the speed of said prime-mover.

5. A liquid dispensing device including in combination a prime-mover; a liquid pump; fluid pressure-responsive means for decreasing the speed of said prime-mover when the operating fluid pressure exceeds a selected value and for increasing the speed of the prime-mover when the operating fluid pressure is less than a selected value, said means being supplied by said pump with fluid at the pressure of the eduction side of said pump; and, clutch means for automatically uncoupling said prime-mover and said pump when the speed of said prime-mover is lowered to a selected value and for automatically coupling said prime-mover and said pump when the speed of said prime-mover is raised to a selected value.

6. A liquid dispensing device including in combination a prime-mover; a liquid pump; means for supplying fluid to said pump; means for dispensing fluid under pressure from said pump; means for automatically decreasing the speed of said prime-mover when the fluid pressure exceeds a selected value and for automatically increasing the speed of said prime-mover when the fluid pressure becomes less than a selected value; and, clutch means for automatically uncoupling said prime-mover and said pump when the speed of said prime-mover is lowered to a selected value and for automatically coupling said prime-mover and said pump when the speed of said prime-mover is raised to a selected value.

7. A liquid dispensing device including in combination a prime-mover; a liquid pump adapted to be driven by said prime-mover; means responsive to the fluid pressure at the eduction side of said pump for controlling the speed of said

prime-mover, said means including a pressure cylinder communicating with the eduction side of said pump, a spring-pressed piston in said cylinder and throttle means adjustably connected to said piston; and, a clutch for automatically coupling and uncoupling said pump and said prime-mover in response to a speed change of said prime-mover.

8. A liquid dispensing device including in combination a wheeled vehicle; a prime-mover and a liquid dispensing pump carried by said vehicle; a clutch for automatically coupling and uncoupling said prime-mover and said pump in response to a speed change of said prime-mover; and, means for automatically effecting a change in the speed of said prime-mover in response to a change in the pumping pressure.

9. A liquid dispensing device including in combination a prime-mover; a pump for moving incompressible fluid material at an elevated pressure from a supply source to a desired locus; fluid pressure-responsive means subject to the pressure exerted by said fluid material for effect-

ing a deceleration of the speed of said prime-mover when said pressure exceeds a selected value and for effecting an acceleration of the speed of said prime-mover when said pressure is less than a selected value; and, a clutch operable when the speed of said prime-mover reaches a selected value to couple said prime-mover to said pump and operable when the speed of said prime-mover falls below said value to uncouple said prime-mover from said pump.

10. A liquid dispensing device including in combination a prime mover; a liquid pump; means for automatically coupling and uncoupling said prime mover and said pump in response to speed changes of said prime mover; and means for optionally disconnecting the pump from the prime mover independently of said automatic coupling means; and means for effecting a change in the speed of said prime mover in response to a change in the pumping pressure developed by the pump.

PHILIP M. CARTER,
HOBART N. DURHAM.
